MIXING SHAKERFloyd E. Pettengill, Lancaster, Ohio, assignor to Afico
S.A., Lausanne, Switzerland, a company of Switzerland

Filed Oct. 19, 1966, Ser. No. 4,333

Term of patent 14 years

(Cl. D9—10)

FIG. 1

FIG. 4

FIG. 1 is an elevational view of a combined storage jar and mixing shaker showing my new design, the opposite side being the same in appearance;

FIG. 2 is an exploded, fragmentary view showing the upper half;

FIG. 3 is an enlarged top plan view with the closure cap removed; and

FIG. 4 is an enlarged top plan view of the closure cap.

The dominant features of my design reside in the portion shown in full lines. Conventional dispensing apertures are shown by means of broken lines in FIG. 3.

I claim:

The ornamental design for a combined storage jar and mixing shaker, substantially as shown and described.
